UNITED STATES PATENT OFFICE

150,331

DESIGN FOR A PORTABLE ELECTRIC STOVE

Michael J. Auer and Tullio Edgar Grade,
New York, N. Y.

Application September 14, 1946, Serial No. 133,326

Term of patent 3½ years

(Cl. D81—10)

To all whom it may concern:

Be it known that we, Michael J. Auer and Tullio Edgar Grade, both citizens of the United States, residing in the Borough and county of the Bronx, city and State of New York, have invented a new, original, and ornamental Design for a Portable Electric Stove, of which the following is a specification, reference being had to the accompanying drawings, forming a part thereof, in which:

Fig. 1 is a perspective view of a portable electric stove embodying our invention, the view showing the front and one end of such stove, and the stove cover in open position; and

Fig. 2 is a perspective view of such stove showing the front and the end opposite from the end shown in Fig. 1, the view further showing the cover in closed position.

The longitudinal side opposite from that shown in Fig. 1 is the same as that shown in Fig. 1 except for the recess shown therein.

We claim:

The ornamental design for a portable electric stove, as shown and described.

MICHAEL J. AUER,
TULLIO EDGAR GRADE.
